UNITED STATES PATENT OFFICE.

SAMUEL J. NEWMAN, OF NEW HAVEN, CONNECTICUT, AND WEBSTER BENJAMIN, OF NEWARK, NEW JERSEY, ASSIGNEES, BY MESNE ASSIGNMENTS, TO I. NEWMAN & SONS, INC., OF NEW HAVEN, CONNECTICUT, A CORPORATION OF CONNECTICUT.

BRASSIÈRE.

Application filed August 11, 1922. Serial No. 581,212.

To all whom it may concern:

Be it known that we, SAMUEL J. NEWMAN and WEBSTER BENJAMIN, both citizens of the United States, and residents, respectively, of New Haven, in the county of New Haven and State of Connecticut, and Newark, in the county of Essex and State of New Jersey, have invented a new and Improved Brassière, of which the following is a full, clear, and exact description.

This invention relates to brassières and has for an object to provide an improved construction in which a pleasing effect is produced and also a binding action for rounding out the figure.

Another object of the invention is to provide a brassière having an elastic vest for temporarily holding the parts in place and means covering the same acting as a binding member for compressing and rounding out certain parts of the body.

A still further object of the invention is to provide an improved brassière arranged with a covering body formed more or less ornamental and co-acting members which co-act with the covering body and with the corset of the wearer to hold the body in a desired form without distorting the covering body.

30 In the accompanying drawings—

Figure 1 is a perspective view of a brassière disclosing an embodiment of the invention.

Figure 2 is a perspective view similar to Figure 1 but showing the covering body open and thrown back.

Figure 3 is a view similar to Figure 2 but showing the clamping band open and thrown back.

40 Figure 4 is a view similar to Figure 3 but showing a slightly modified structure with the parts open and somewhat spread out.

Figure 5 is an enlarged sectional view through Figure 1 approximately on line 5—5.

Figure 6 is a perspective view of a modified form of brassière to that shown in Figure 4.

50 Figure 7 is a horizontal sectional view through the brassière shown in Figure 6 as the same would appear when in use.

Referring to the accompanying drawings

by numeral, 11 indicates a body provided with a back portion 12 merging into the 55 sides of the front portions or flaps 13 and 14. The body is provided with suitable openings 15 and 16 acting as arm openings through which the arms are passed when the device is to be used. It will be noted from the drawing that the body 11 is cut to properly fit the figure so that the front portions 13 and 14 overlap to a desired extent. In order to bring these front portions under some tension, they are provided with hooks 60 or other securing members 17 and 18 adapted to hook into the respective eyelets 20 and 19 of the front flap 14 and of the supporting or restraining band 21. In order to draw together or move under tension the upper part of the front flaps or portions 13 and 14, a hook 22 is secured to a suitable tape or other mounting 23 which is secured to the under side of the flap or front portion 13, said hook 22 being adapted to be 70 interlocked with the retaining member 24 which is provided with a series of apertures for receiving the hook.

The body 11, with its overlapping front portions or flaps 13 and 14, forms a more 80 or less ornamental covering or brassière body but sometimes the person wearing the garment is more or less unshapely and, consequently, this structure would not properly support that part of the body with which 85 it comes in contact. To bind in the body near and above the waist line, the supporting or clamping band 21 is provided, which is divided into two parts and the respective parts secured by suitable lines of stitching 90 to the body 11 near the sides thereof, said sections extending over the front where they may be drawn toward each other by suitable lacing 25. Before the lacing 25 is utilized, the garment may be supported on a 95 person by elastic sections 26 and 27 which are connected to the body 11 near the sides by stitching or other suitable means, said elastic sections being of substantially the same width as the band 21. In Figure 3, 100 suitable snap fasteners 28 are provided for holding the sections 26 and 27 together, said snap fasteners being arranged to one side of a central line so that they will not appear beneath the opening left by the lacing 25. 105 It will, therefore, be noted that the section

27 is of less length than section 26. In Figure 4, both of the sections 26 and 27 are of the same length so that the snap fasteners 28 in this form of the invention will be centrally of the garment or directly in front of the person using the article.

In use when the article is first placed in position on a person, the fasteners 28 are properly interlocked and when this has been 10 done it will be noted that the elastic sections 26 and 27 are under tension. The band 21 is then laced and as it is laced the ends are drawn towards each other until the sections 26 and 27 have been relieved of substantially 15 all tension thereon so that the band 21 will act as a support or clamping member for holding that part of the body positioned adjacent the band in a rounded position and also in such a manner as not to distort the 20 flaps 13 and 14 which are later folded over the support 21.

In corsets as now commonly used, the 25 waist line of the corset is only a few inches below the top of the corset and, consequently, the body of the person wearing the corset above the waist line is left unsupported. The supporting band 21 is designed to extend down to approximately the waist line 30 of the corset and to co-act with the corset in binding in part of the body of the person immediately above the corset so that the flaps or front portions 13 and 14 will not be distorted.

In Figures 6 and 7 will be seen a further 35 modified form of the invention to that shown in Figure 4 wherein the construction is identical except for the restraining members 34 and 35, which restraining members are of elastic material provided with 40 suitable fastening means similar to the structure shown in Figure 4. The restraining members 34 and 35 are arranged so that the fastening members 36 will be centrally of the body when in use as shown in Figure 7. These elastic members are secured 45 to the two sections 37 and 38 of the restraining band 21 along the lines 39 and 40. It will thus be seen that the sections 37 and 38 are stitched to the body of the brassière beneath the arms and along the lines 41 and 50 42 but the elastic sections are secured in place an appreciable distance forwardly therefrom on the band 21. This will permit a proper functioning of the elastic sections

without adding thickness or unnecessary 55 large seams at the sides.

What we claim is:—

1. A brassière, comprising a body formed with a pair of overlapping front flaps, means at the lower part of said flaps for 60 holding the flaps in overlapping position, adjustable means near the top of said flaps for adjustably connecting the flaps together near their upper parts, an elastic vest connected to said body near the sides and positioned to extend across the front of the garment, and an adjustable support connected to said body near the sides and extending across the front of the garment, said adjustable support being positioned between 70 said flaps and said elastic vest.

2. A brassière of the character described, comprising a body open at the front and provided with overlapping sections at the front, a pair of restraining members secured 75 to said body near the sides, means for drawing the front edges of said restraining members towards each other, a pair of elastic members meeting at the front of said body for temporarily holding the brassière on a 80 person, and means for connecting said elastic members together at their point of meeting.

3. A brassière, comprising a body open at one point from top to bottom, a restraining 85 band divided into two sections, said sections being connected respectively to the opposite sides of the body, lacing at the front for connecting said sections together, and an elastic restraining member secured 90 to each of said sections and fastening means for connecting the elastic members together.

4. A brassière of the character described, comprising a body open at the front, means for securing the parts of said body together, an inelastic restraining member connected to each side of said body and an elastic restraining member connected to each section of said inelastic restraining member, each elastic member being provided with 100 fastening means for connecting the elastic members together when the garment is in use, and lacing for holding said inelastic restraining member in position when in use, said lacing acting to take the strain off of 105 the elastic members.

SAMUEL J. NEWMAN.
WEBSTER BENJAMIN.
